UNITED STATES PATENT OFFICE.

WILLIAM M. WARNER, OF YONKERS, NEW YORK.

BUCKLE.

SPECIFICATION forming part of Letters Patent No. 711,748, dated October 21, 1902.

Application filed February 7, 1900. Serial No. 4,401. (No model.)

To all whom it may concern:

Be it known that I, WILLIAM M. WARNER, a citizen of the United States of America, and a resident of the city of Yonkers, county of 5 Westchester, and State of New York, have invented certain new and useful Improvements in Buckles, of which the following is a specification.

The buckle herein described and claimed 10 is intended, primarily, to hold the edge or fold of fabrics, so that it shall serve as a holder for bedclothes or as a fastener for towels, stockings, or the like.

The invention consists in the combination 15 of a frame and tongue, as hereinafter particularly described, and defined in the claims.

In the accompanying sheet of drawings, which forms a part of this specification, Figure 1 is a perspective view of the buckle. 20 Fig. 2 is a view illustrating the buckle and the edge of a bed-cover engaged thereby. Fig. 3 shows a part of a bed and cover and a buckle holding the cover, the buckle being tied to a bed-post.

25 In the form shown the frame of the buckle is a ring *a*, upon which the tongue *b* is hinged at *c*. The movement of the tongue on its hinge permits it to be lifted from the ring, and it may be reversed and lie across either 30 side of the ring. This movement will be termed the "angular" movement. It can also be moved around the ring circumferentially. This circumferential movement in addition to its function in locking the tongue, 35 as hereinafter described, also serves to permit the fabric to be passed through the ring in any position thereof and the tongue to move around the ring to properly engage it. The tongue overlies the frame, or, in other 40 words, the end of the tongue projects beyond the inner margin of the frame, and is in this respect different from the ordinary buckle in which the end of the tongue closely coincides with the inner margin of the frame, and the 45 fabric is clamped between the end of the tongue and the inner margin of the frame.

A head *d* is formed on the end of the tongue, and since the head is larger than the shank of the tongue shoulders *e* are formed on the 50 tongue between its head and hinge. These shoulders may be on the top and bottom, as

shown. The shoulders may be formed both at the sides, top, and bottom by providing a ball-shaped head to the tongue.

In the form of my invention shown the end 55 of the tongue not only projects beyond the inner margin of the frame, but also beyond the outer margin thereof, and the shoulders *e*, formed by the head, are also beyond the outer margin of the frame, and one shoulder 60 is adjacent thereto when the bracket is in position for use, a portion of the head at that time projecting below the frame itself.

The tongue is extended on the opposite side 65 of the hinge from the head, where it is provided with an eye *f* for the attachment of a cord or tape, by which it is connected to its support—as, for example, to the bed-post—as shown in Fig. 3. Any other suitable form of connection may be substituted for the eye and 70 tape.

The outline of the frame is not necessarily 75 that of a circle; but it is desirable that it should be so formed that there will be a considerable opening on each side of the tongue, so that the edge or fold of a heavy fabric or 80 several thicknesses of fabric can be passed through the ring and over the head of the tongue.

When the fabric is passed through the frame 80 and over the head of the tongue, as shown in Fig. 2, the edge lodges back of the shoulder, and the fabric is wrapped over the head of the tongue and around the inner margin of the frame. The friction due to this wrapping 85 is sufficient to securely hold the fabric against dislodgment, owing to the engagement of the edge back of the shoulder, and the transverse tension along the edge which holds it in place. This friction upon the head, rather than a 90 bite or grip between the tongue and frame, is relied upon to hold the fabric, since it is thereby held without injury. Means are, however, provided by which the tongue can be prevented from lifting away from the 95 frame when the tension on the fabric is slackened. This consists in slots *g* on each side of the hinge-hole and a flat place *h* at one point of the ring. By turning the ring circumferentially the flat place is passed into 100 the slots and the tongue thereby locked against angular movement with respect to the

ring, thus preventing the tongue from lifting away from the ring in event of the slackening of the tension on the tapes and fabric and the fabric thereby given an opportunity to 5 work loose.

Having now described my invention, what I claim as new, and desire to secure by Letters Patent of the United States, is—

1. A buckle consisting of a frame and a tongue having relative circumferential and angular movements, and means, operative on a circumferential movement of the frame and tongue, to lock the said parts against angular movement, substantially as described.
- 15 2. A buckle consisting of a ring, and a tongue having a hole through which the ring passes, capable of angular and circumferential movement upon the ring, substantially as described.
- 20 3. A buckle consisting of a ring, and a tongue having an angular aperture through which the ring passes and the ring having a

portion angular in cross-section to lock the tongue, substantially as described.

4. A buckle, consisting of a frame and 25 hinged tongue, the tongue overlying the upper surface of the frame and having a part upon its end projecting beyond the outer margin of the frame and located below the upper surface thereof, substantially as described. 30

5. A buckle consisting of a frame and tongue, the two being hinged together, the tongue overlying the upper surface of the frame and being provided with a head beyond the outer margin of the frame, a part of the 35 head being located below the upper surface of the frame, substantially as described.

Signed by me at Yonkers, New York, this 6th day of February, 1900.

WILLIAM M. WARNER.
